UNITED STATES PATENT OFFICE.

JESSAMINE QUIGLEY, OF HAMMOND, INDIANA.

BUST-FORM.

SPECIFICATION forming part of Letters Patent No. 638,400, dated December 5, 1899.

Application filed June 16, 1899. Serial No. 720,785. (No model.)

To all whom it may concern:

Be it known that I, JESSAMINE QUIGLEY, a citizen of the United States, residing at Hammond, in the county of Lake and State of Indiana, have invented a new and useful Improvement in Bust-Forms, of which the following is a specification.

This invention relates to a bust-form, and has for its object to provide a simple and effective device of this character as an artificial means of correcting the irregularities of physical development and the use of which will baffle detection by reason of the fact that the parts are maintained in regular or symmetrical form by the regular interposition of yielding devices, which are caused to effect their function almost completely to the shoulder-seams and fully to the scyes or armholes, and thus avoid gaps or external irregular appearance, and with perfect comfort to the wearer.

The invention consists in the construction and arrangement of parts, which will be more fully hereinafter described and claimed.

In the drawings, Figure 1 is a perspective view of the improved device shown applied and looking toward the front thereof. Fig. 2 is a side elevation of the same. Fig. 3 is a back view of the improved device.

Similar numerals of reference are employed to indicate corresponding parts in the several views.

The numerals 1 and 2 represent the opposite front sections or members, each having sufficient material therein to accommodate the interposition of yielding distending devices which will be presently described and embodying a particular arrangement which will cause the sections 1 and 2 to maintain the projecting contour given them by the initial arrangement. Each section has a curved neck-recess 3, a central downward extension 4, and a partial scye or armhole curved recess 5. From the lower portion of the front overlapping edges 6, of each section, the lower marginal line 7 curves downwardly in regular contour through the extension 4 and then upwardly to the under-arm location, and terminates and becomes continuous with the under straight edge 8 of a seam-flap 9, which includes a part of the recess 4. From the flap 9 the contour of each section toward the

point 10 of greatest distention conforms to or is patterned after the lines of a perfectly-developed bust, and from said point of greatest distention the slope and curvature are regular toward the shoulder-seam 11 on each side. The greatest width or expanse of material is also confined between each of the edges 6 and the flaps 9, and the portion 12 of the material which extends upwardly from said greatest point of distention toward the shoulder-seam 11 is narrowed and includes therein a portion of both the neck-recess 3 and the scye or arm-hole recess 5, which are the opposite margins of this part of each section. From the point 10 of greatest extension 10 each section slopes inwardly, as at 13 and clearly shown by Fig. 1, and it will be understood that all the curves and slopes gradually merge off or are of less surface extent in the direction toward the scyes or armholes and the under-arm portions.

While the interposed yielding devices stiffen the sections 1 and 2 to a greater or less degree, it will be understood that they do not create any discomfort when the device is in use, and said sections when applied in operative position regularly receive and support the garment placed thereover in a manner similar to the application of such garment to a natural form. The under-arm portions 80 of the improved bust-form are reduced in downward extent to avoid a bulky or unnatural appearance, which is clearly shown by Fig. 2, and to support the sections 1 and 2 they are connected to a back 14, which is 85 made up of a single thickness of suitable material and has the scye or armholes partially formed therein.

Flaps 15 are extended across the shoulders and meet the upper reduced terminals of the sections 1 and 2 at the front, so as to avoid an unpleasant bearing or pressure on the shoulders of the wearer. Side flaps 16 are also extended forwardly from the lower portions of the back and meet and are connected 95 to the flaps 9 of the said sections. The downward extent of the back 14 is considerably less than that of the sections 1 and 2, and the improved device is thus rendered cool and greater ventilation is permitted at a point 100 where necessary.

The sections 1 and 2 are connected at the

front preferably by means of hooks, though other fastening devices may be used, and the inner lining or that portion of the sections which are adjacent the body of the wearer 5 will have a contour conforming to the latter. The material of which the improved device is constructed may be varied to suit different tastes, but is intended to be of a nature sufficiently durable to withstand wear arising 10 from continued usage.

Bust-forms as heretofore constructed have usually been held in place by shoulder or body straps or other devices which would slip and permit the bust portion of the form 15 to become displaced, and particularly adjacent the shoulders. By providing the back 14 in the present construction the form is held against movement after proper application, and it will be observed that the said 20 back extends far enough down to provide for the formation of armholes, which will prevent the slipping movement referred to and also avoid entirely covering the back of the wearer, as it is only essential that the said 25 back 14 extend a little below the armholes. This back 14, as previously set forth, will be made of some light material, and by curtailing its extent in a downward direction the wearer will not be inconvenienced by the extra 30 thickness of material that would result if said material extended downwardly equal to the bust-form proper.

The distending devices, as shown by the drawings, have no special construction or arrangement; but such parts will be similar to devices now commonly known in the market, and their arrangement will be in accordance with the desired shape, care being taken to 35 avoid a bulky assemblage adjacent the front-

shoulder and under-arm portions of the improved form. 40

In making up the improved device it will be produced in view of a scale measurement to adapt it to various forms and to properly size it, and the covering material may be of 45 an expensive nature or an inferior quality. These matters will be regulated entirely by the demand of the trade; but under all conditions the salient features will be preserved, and are the front sections having the lower 50 extensions and under-arm projections, as well as the front-shoulder portions, all distended and gradually shaped off and supported by and connected to a flexible back which has less downward extent than the said front sections. 55

Having thus described the invention, what is claimed as new is—

A bust - form comprising front sections adapted to be separably joined at the center 60 and each regularly distended to simulate the human form and having therein devices for maintaining the desired contour, neck and armhole recesses being partially formed in each section, and a back composed of a piece 65 of material having portions extended across the shoulder part of the form and connected with the upper front portion of the said sections and also provided with a portion of the neck and armholes to continue with those in 70 the sections, the said back extending downwardly only a short distance below the location of the armholes of the form.

JESSAMINE QUIGLEY.
